NONREFILLABLE BOTTLE

Ludwig A. Ihlein, Philadelphia, Pa.

Application April 6, 1938, Serial No. 200,382

8 Claims. (Cl. 215—17)

The object of this invention is to devise a novel non-refillable attachment which can be applied to the neck of a bottle and which will provide for a free flow of the liquid during normal use, but which, when the bottle is empty, will prevent the refilling of the bottle.

A further object of the invention is to devise a novel non-refillable mechanism which can be economically manufactured, which is fool proof, and which will be reliable and accurate in operation.

With the above and other objects in view as will hereinafter clearly appear, my invention comprehends a novel non-refillable bottle.

It further comprehends novel non-refillable mechanism having means to positively lock it in sealed position when the liquid in the bottle has been dispensed.

Other novel features of construction and advantage will hereinafter clearly appear in the detailed description and the appended claims.

For the purpose of illustrating the invention, I have shown in the accompanying drawing, a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

Figure 1 is a sectional elevation of a bottle with the non-refillable mechanism in position.

Figure 2 is a sectional view showing the parts in inverted position and the bottle portion in section.

Figure 3 is an exploded view of parts of the non-refillable mechanism.

Figure 4 is a sectional elevation on an enlarged scale of assembled parts of the non-refillable mechanism.

Figure 5 is a sectional view on an enlarged scale of certain parts of the mechanism.

Figure 6 is a sectional view on an enlarged scale of another embodiment of the invention.

Figure 7 is a top plan view of a disc and valve forming part of the mechanism.

Figure 8 is a sectional view of a portion of the vent tube on an enlarged scale.

Similar numerals indicate corresponding parts. Referring to the drawing:

The casing or body portion is in the form of a split sleeve having the sections 1 and 2 which are provided on their inner faces with grooves 3, 4, 5 and 6. The outer groove 3 receives an aper-

tured disc 7 fixed to a discharge tube 8. An inlet tube 9, in communication with the liquid in a bottle 10, has an apertured disc 11 to seat in the groove 6. A valve 12 has a stem passing into the inlet tube 9 with suitable clearance with the inner walls of such tube 9. The valve 12 has longitudinally extending, circumferentially spaced grooves 13 in its outer periphery and its bottom face is adapted to normally rest on the disc 11 and close the opening through the inlet tube 9.

14 designates a tubular baffle having an apertured disc 15 to seat in the groove 4. The outer end of the baffle 14 forms a conical head 16, and between such head and the disc 15 is an annular groove 17, which opens into the bore of the baffle through a port 18. A valve 19, having its outer end coned, is slideable in the baffle, and has, at its lower end, flexible prongs 20 having catches 21, which, when the valve 19 is pushed all of the way inwardly, will lock with the bottom walls of an apertured disc 22 seated in the groove 5.

23 designates a vent tube fixed to the inner wall of a casing section in any desired manner. The upper end of the vent tube preferably terminates below the upper end of the casing, and its lower portion extends into the liquid in the bottle. The vent tube has an opening 24 at its lower portion, controlled by a locking sleeve 25 slidably on the vent tube, and has its downward movement limited by a stop 26 on the vent tube. The locking sleeve 25 is carried by a float 27, which carries at its upper end a spring catch 28, which cooperates with a shouldered lug 29 on the vent tube, having a rounded lower portion. The vent tube has a ball valve 30 which engages a seat 31 when the bottle is upright, and which moves against a stop 32 when the bottle is inverted. The vent tube has an aperture 33 in its side wall opening into the casing and this aperture can be permanently sealed by a locking tube 34 having a working fit in the vent tube. The locking tube 34 is moved into locked position by a tube 35 which contacts the irregularly shaped end of the locking tube 34.

The casing sections are secured in any desired manner in an outer sleeve 36. This may be accomplished by soldering or welding if the parts are metallic or by cementing or interlocking such parts in any desired manner for example by indenting one into the other. The outer sleeve secures the part as an assembled unit, and such outer sleeve is permanently fixed in the neck of the bottle in any desired manner, for example by

cementing or casting it in place or by a threaded engagement as shown in Figure 6.

The different discs are notched to provide clearance for the vent tube.

5. The locking sleeve 25 has a cut out portion 37. The tube 34, see Figure 8, may have an aperture 38.

The operation will now be readily apparent to those skilled in this art and is as follows:

10. Assuming that the non-refillable mechanism has been permanently fixed in the neck of a bottle containing the liquid to be dispensed, and the operator inverts the bottle, the liquid will freely flow through the inlet tube 9, as the valve 12 has 15 moved forwardly away from the disc 11, into the baffle 14, through port 18 into the casing around the head 16 along the outer end of the valve 19 and through the discharge tube 37. The cork 27 rides up towards the bottom of the bottle when the 20 bottle is inverted, so that the cut out portion 37 of the sleeve 25 connected with the float uncovers the aperture 24 of the vent tube to provide for the proper venting through the vent tube.

- The cut out portion 37, leaves a narrow strip 25 which does not cover the port 24 in the vent tube 23. When the parts are in the position seen in Figures 1 and 4, the vent aperture 24 is open and when the float 27 moves towards the bottom of the bottle when the bottle is inverted, the port 24 is still open. The spring catch 28 engaging the stop 29, limits the upward movement of the float when the bottle is in an upright position. When the liquid in the bottle has been dispensed, the operator gives the bottle an abrupt 35 shake with the bottle inverted, and the spring catch 28 will move down below the stop 29 and thus cause the sleeve 25 to close the port 24 and thereby prevent the venting action of the vent tube.

- If the liquid has been dispensed, the non-refillable mechanism can be permanently locked by pushing in on the valve 19 to cause the spring catches 20 to pass through the opening in the fixed disc 22 and the catches or prongs 21 will 45 lock against the bottom face of such disc. Since the members 20 when in this position, press the valve 12 against its seat on the disc 11, liquid can not pass from the bottle through the inlet port 9.

- I also provide means to prevent refilling of the 50 bottle, namely the tubes 34 and 35.

- When the tube 35 is moved downwardly it pushes the tube 34 downwardly to bring the aperture 38 into registry with the aperture 33 of the vent tube. If a suction is created at the upper 55 end of the vent tube air will be drawn from the interior of the body portion and the bottle cannot be refilled.

- If a pressure is applied to the upper end of the vent tube the ball 30 will be pressed against its seat 31.

The valve 19 or the tubes 34 and 35 or both of such parts can be omitted if desired.

- The member 36 may be provided with means to prevent its being unscrewed as shown in Figure 6, one way of accomplishing this result being the indentations illustrated.

- The baffle and also the valve 19, if employed, prevent the insertion of a wire or other instrument to attempt to hold the valve 12 in its open position.

Having thus described my invention, what I claim as new and desire to secure by Letters Patent is:—

1. A non-refillable bottle mechanism, compris-

ing a body portion, a delivery tube fixed within one end of said body portion, an inlet tube fixed within the inlet end of said body portion, a baffle between said tubes, a vent tube in the body portion, extending into the liquid in the bottle and having an aperture, a float slideable on the vent tube and having means to control the vent aperture, a stop, and a catch carried by the float and locking with said stop to cause said float means to permanently close the vent aperture when the liquid in the bottle has been dispensed.

2. A non-refillable bottle mechanism, comprising a body portion, a delivery tube fixed within one end of said body portion, an inlet tube fixed within the inlet end of said body portion, a baffle between said tubes, a valve to close the inlet tube, means to permanently seat the valve in closed position when the liquid in the bottle has been dispensed, a vent tube in the body portion, extending into the liquid in the bottle and having an aperture, a float slideable on the vent tube and having means to control the vent aperture, a stop, and a catch carried by the float and locking with said stop to cause said float means to permanently close the vent aperture when the liquid in the bottle has been dispensed.

3. A non-refillable bottle mechanism, comprising a body portion, a delivery tube fixed within one end of said body portion, an inlet tube fixed within the inlet end of said body portion, a baffle between said tubes, a vent tube in the body portion, extending into the liquid in the bottle and having an aperture, a float slideable on the vent tube and having means to control the vent aperture, a stop, a catch carried by the float and locking with said stop to cause said float means to permanently close the vent aperture when the liquid in the bottle has been dispensed, said vent tube having an upper aperture opening into the body portion, and means to close the vent tube below said upper aperture and to bring the upper portion of the vent tube into communication with said upper aperture.

4. In a non-refillable bottle mechanism, a body portion, a valve having limited movement in the body portion and controlling discharge from the bottle, a tubular baffle above said valve having a side discharge port, a second valve controlling said side port, and slidably mounted in said baffle, means to lock said second valve in its inward position and thereby retain said first valve in closed position, a vent tube extending from the body portion into the liquid in the bottle and having an aperture, a float slideable on said vent tube, a sleeve connected with said float and controlling said aperture, a stop, and a spring catch on the float cooperating with said stop to limit movement of the float and to lock the float in a position to have its sleeve close the vent tube aperture.

5. In a non-refillable bottle mechanism, a sectional body portion, an outer sleeve secured to the body portion and adapted to be permanently fixed in a bottle neck, a valve having limited movement in the body portion and controlling discharge from the bottle, a baffle above the valve forming with the body portion a circuitous discharge passage, a vent tube extending from the body portion into the liquid in the bottle, having a lower aperture below the level of the liquid, and having an upper aperture opening into the body portion, a float controlling said lower aperture, and a member to close the vent tube below the upper aperture and to bring the vent tube

above the upper aperture into communication with the interior of the body portion.

6. In a non-refillable bottle mechanism, a body portion, inlet and discharge tubes fixed in the body portion, a valve having a stem extending into the inlet tube and longitudinally extending grooves in its body, an apertured disc limiting movement of said valve, a tubular baffle outwardly of said disc, a valve controlling said baffle and having means to pass through and engage said limiting disc and to seat said first valve in its closed position, and a vent tube having its lower end closed and having an aperture, and a float controlling said aperture of the vent tube.

7. In a non-refillable bottle mechanism, a body portion, inlet and discharge tubes fixed in the body portion, a valve having a stem extending into the inlet tube and longitudinally extending grooves in its body, an apertured disc limiting movement of said valve, a tubular baffle outwardly of said disc, a valve controlling said baffle and

having means to pass through and engage said limiting disc and to seat said first valve in its closed position, a vent tube having its lower end closed and having an aperture, and a float controlling said aperture of the vent tube, and an outwardly opening check valve in said vent tube. 5

8. In a non-refillable bottle mechanism, a sectional body portion, means to secure the sections assembled, an upper and a lower flanged tube in the body portion, a valve controlling the lower tube, a vent tube in the body portion and extending into the bottle with a closed end and an aperture above said closed end, a float on the tube controlling said aperture and having means to lock it in position to close said aperture, said 10 vent tube having a port opening into the interior of the body portion, and a sectional locking tube in the upper end of the vent tube, one section of which has an aperture to communicate with the vent aperture opening into the body 15 portion. 20
